UNITED STATES PATENT OFFICE.

MATTEO L. DALPEZ, OF TELLURIDE, COLORADO.

CUSPIDOR.

1,055,141.

Specification of Letters Patent.

Patented Mar. 4, 1913.

Application filed October 12, 1912. Serial No. 725,494.

To all whom it may concern:

Be it known that I, MATTEO L. DALPEZ, a subject of the Emperor of Austria-Hungary, residing at Telluride, in the county of San 5 Miguel and State of Colorado, have invented certain new and useful Improvements in Cuspidors, of which the following is a specification, reference being had to the accompanying drawings.

10 This invention relates to new and useful improvements in cuspidors and more particularly to a cuspidor provided with means to prevent the contents thereof from being spilled as said cuspidor is tilted or upset 15 from any direction.

A further object of the invention resides in providing a plurality of gravity valves, one of which is adapted to be seated over the opening in the cuspidor when the same 20 is tilted or upset and a still further object of the invention resides in pivotally mounting said valves in such a position in the cuspidor as to allow one of the same to form a retaining means for the other valve forming 25 a closure for the opening when the device is upset.

Still another object of the invention resides in the provision of a device which is extremely simple and durable in construction, inexpensive to manufacture and one 30 which will be very efficient and useful in operation.

With these and other objects in view, the invention consists in the novel features of 35 construction, combination and arrangement of parts as will be hereinafter referred to and more particularly pointed out in the specification and claim.

In the accompanying drawing forming a 40 part of this application, Figure 1 is a vertical section through the device. Fig. 2 is a horizontal section therethrough as seen on line 2—2, Fig. 1; and Fig. 3 is a vertical section through the device showing the 45 same in upset position.

In describing my invention, I shall refer to the drawing in which similar reference characters designate corresponding parts throughout the several views and in which 50 1 indicates a substantially cylindrical cuspidor formed of the upper and lower sections 2 and 3 respectively, said sections being threaded together as shown at 4 and the top 5 of the cuspidor is inclined toward

the axial center of the device as usual, and 55 provided with a central opening 6.

Hinged to the inner wall of the cuspidor immediately adjacent the top 5 thereof and spaced equally from one another there-around, is a trio of arms 7, the lower free 60 ends of which are bent inwardly as shown at 8 and have secured thereto, the hemi-spherical weighted members 9. Each of the arms 7 is of such length that when the same is swung inwardly toward the axial center 65 of the device, the hemi-spherical weight member 9 thereon is adapted to fit tightly in the opening 6 to form a closure or valve therefor, and a rubber washer or the like 70 is provided on the peripheral edge of 70 this opening 6 to allow these weighted valve members 9 to contact therewith without undue noise.

It will be understood that but one weight member 9 may be seated over the opening 75 6 to form a closure or valve therefor, but when the device is tilted so that one of said members is in such position, another of the weight members is adapted to rest on the last mentioned weight member to retain the 80 latter in its position over the opening.

In practice, the lower section 2 will first be filled with water or any other liquid matter and the upper section 3 securely engaged therewith and in the normal position 85 of the device, as shown in Fig. 1 of the drawing, the arms 7 hang downwardly against the inner face of the wall thereof. Should for any reason whatsoever, the device be tilted or entirely upset from any 90 direction, at least two of the gravity or weighted valve members 9 will drop toward the axial center of the device, one of said members actually covering the opening 6 and the other falling on the last mentioned member to securely retain the same in position, as clearly shown in Fig. 3 of the drawing. It will thus be appreciated that the liquid within the device cannot be splashed through the opening at the time 100 of tilting and cannot flow therefrom at the complete upsetting of the device.

From the foregoing it will be seen that I have provided a simple, inexpensive and efficient means for carrying out the objects 105 of the invention and while I have particularly described the elements best adapted to perform the functions set forth, it is ob-

vious that various changes in form, proportion and in the minor details of construction may be resorted to without departing from the spirit or sacrificing any of the 5 principles of the invention.

Having thus described this invention, what I claim is:—

A cuspidor of the class described comprising a cylindrical body member provided 10 with the usual inclined top, said top having a central opening therein, a plurality of arms hingedly engaged at their upper ends with the wall of said body immediately adjacent the top thereof, the lower ends of said 15 arms being extended below the plane of the opening in said top and bent inwardly to-

ward the axial center of the device, and hemi-spherical weight members mounted on the inwardly bent ends of said arms, one of said weight members being adapted to be 20 seated over the opening in the top when said body is tilted and another of said weight members being adapted to rest on the last mentioned weight member in this position of the body to retain the first mentioned 25 weight member in position over the opening.

In testimony whereof I hereunto affix my signature in the presence of two witnesses.

MATTEO L. DALPEZ.
